UNITED STATES PATENT OFFICE.

JOSEPH E. ZOMNIR AND CLARENCE L. PFERSCH, OF SPRINGFIELD, MASSACHUSETTS,
ASSIGNORS TO THE DIAMOND MATCH COMPANY, OF CHICAGO, ILLINOIS, A COR-
PORATION OF ILLINOIS.

MATCH-MAKING MACHINE.

Application filed May 27, 1927. Serial No. 194,617.

This invention relates to machines for making cards or strips of matches which are used more especially in the manufacture of so-called book matches; having particular reference to means for providing the match splints with paraffin effective to transmit the flame from the heads to the bodies of the respective splints. The paraffin-applying means heretofore generally employed has supplied an excessive abundance of paraffin to the stock or to the cards or strips of splints severed therefrom; that is to say, the stock, or the severed cards or strips of splints, have been supplied with paraffin by partially immersing the stock or the splints in molten paraffin or by applying the paraffin to and along both sides of the stock as the splints or the stock progress to or through the match making instrumentalities. We have discovered that the application of a relatively small quantity of paraffin to a match splint, contiguous to the ignition head, is sufficient to transmit the flame effectively from the head to the body of the splint; and therefore the object of our invention is to provide simple and efficient means whereby paraffin is economically applied to the match stock at regular intervals in such a manner that when the stock is subjected to the action of the splint and card cutting mechanism the succeeding rows of splints are provided at their free ends with small quantities of paraffin.

Accordingly the invention comprises novel features of construction and combinations of parts which will be hereinafter described and claimed.

In the drawings—

Figure 1 is a side elevation, partly in section, of a match making machine equipped with paraffin-applying mechanism embodying a preferred form of our invention.

Fig. 2 is a transverse vertical section, through the said mechanism, as on the line 2—2 of Fig. 1.

Fig. 3 is a vertical section through the mechanism as on the line 3—3 of Fig. 2.

Fig. 4 is a similar section, as on the line 4—4 of Fig. 2, showing the parts in their relative positions when the cam actuated pressure roll is clear of the underlying match stock.

Fig. 5 is a perspective view of the pressure and paraffin-transfer rolls, showing a

part of the cam and bar connections for operating the pressure roll, and showing also the treated match stock as formed with match splints at its leading end preparatory to the severance of a strip or card of splints from the stock.

Fig. 6 illustrates the severed strip or card, as reversed, showing the paraffined portions of the splints.

Fig. 7 is a detail, in perspective, of one of the cam shaft boxes, showing the guide thereon for the adjacent cam actuated bar.

Referring to the annexed drawings, 10 designates a portion of the supporting frame, and 11 designates the main driving shaft of a match making machine. 12 designates a portion of the travelling endless carrier by means of which the cards or strips, C, of match splints are carried through the composition applying and drying zones, and 13 designates the feed rolls for the match stock S. 14 designates the splint cutters by means of which the leading end of the stock is cut longitudinally in equally spaced parallel lines to form the match splints m; and 15 designates the cutter blade by means of which the leading end portion of the stock, after it is longitudinally cut and delivered to the carrier, is transversely severed from the body of the stock to provide a card or strip of connected match splints, as seen in Fig. 6. The mechanism just referred to may be of any usual or approved construction.

Located on the supporting frame, in advance of the feed rolls and immediately below the horizontal path of the match stock, is a tank 16 adapted to contain paraffin, which tank is provided with a steam jacket 17 effective to maintain the paraffin in a liquid state, and also with an overflow pipe 18 to ensure a uniform level of the paraffin within the tank.

Mounted in suitable bearings 19 at the respective ends of the tank, are the trunnions of a paraffin-transfer roll 21 which is almost entirely submerged in the liquid contents of the tank, the upper peripheral portion of the roll lying in a plane slightly below the undersurface of the match stock, so that if the intermittently travelling stock be periodically depressed above the roll 21, the film of paraffin on the periphery of the latter will be transferred at spaced intervals to the opposing surface of the stock.

The preferred means for periodically depressing the match stock is as follows: Overlying the path of the stock, directly above and parallel with the transfer roll 21 is a pressure roll 22 the trunnions of which are journaled in blocks 23 having vertical guide-ways 24 which are slidably fitted to parallel standards 25 on the ends of the tank. The bearings 19 previously referred to are preferably constituted by integral depending portions of the standards 25. The blocks 23 are jointed, as at 26, to the lower ends of vertically-movable bars 27 having on their inner faces suitably-disposed anti-friction rolls 28. These rolls 28 extend into the races 29 of a pair of face cams 30 fast on a shaft 31 having its bearings in boxes 32 slidably supported in the respective standards 25. Vertical adjustment of the boxes can be nicely effected by means of overhanging screws 33 threaded in cross-pieces 34 at the tops of the respective standards. Each of the boxes is provided on its inner face with a rectangular guide piece 35 which is slidably fitted in a vertical slot 36 in the adjacent bar 27 so as to guide the bar in its vertical movement. The shaft 31 is provided with a sprocket wheel 37 which is connected by means of a chain 38 with a sprocket wheel 39 on a lower shaft 40 journaled in basal bearings 41 of the respective standards. Fast on one end of the shaft 40 is a bevel gear 42 in mesh with a similar gear 43 on the upper end of an inclined shaft 44, the lower end of which latter shaft, in turn, is provided with a bevel gear 45 in mesh with a similar gear 46 on the main shaft 11.

From the foregoing it will be seen that during the operation of the match machine motion is transmitted from the main shaft 11 to the cam shaft 31, and that the cams rotating with the latter actuate the bars 27 in a manner to raise and lower the pressure roll 22. The cam races 29 comprise acting and dwell portions z , y , respectively, the former effecting the raising and lowering of the bars 27 during each interval of rest of the match stock, and the portions y maintaining such bars in raised position during each advancement of the stock by the feed rolls 13 toward the cutters and the match carrier. In the descent of the bars 27 the pressure roll 22 bears upon and across the match stock S so as to press it against the opposing periphery of the transfer roll 21, which latter roll thus applies a streak of paraffin z to the under surface of the stock, the space between succeeding streaks being such that when the splints and cards are cut from the stock the under surface of the free end of each of the splints is economically provided with just sufficient paraffin to ensure the transmission of the flame from the match head to the body of the splint. (See Figs. 5 and 6.)

The advancement of the depressed stock

by the feed rolls after the pressure roll 22 is raised tends partially to rotate the transfer roll 21 which presents a fresh film of paraffin to the next succeeding portion of the stock when the latter is again depressed by the roll 22.

It is to be understood that our invention is not limited to the particular construction herein disclosed, as the same may be modified within the principle of our invention and the scope of the appended claims.

We claim:

1. In a match making machine having a carrier for the match splints, splint cutting mechanism, and means for feeding a web of match stock to said mechanism and the carrier, a paraffin containing tank located in advance of the said mechanism, directly below the path of the web of match stock, a paraffin transfer element in said tank, and means for effecting relative vertical movement between the web of match stock and the transfer element, whereby said element successively acts upon spaced-apart portions of one surface of the web. 90

2. In a match making machine having a carrier for the match splints, splint cutting mechanism, and means for feeding a web of match stock to said mechanism and the carrier, a paraffin containing tank located in advance of the said mechanism, directly below the path of the web of match stock, a paraffin transfer roll mounted to rotate in said tank, a pressure member overhanging the path of the web directly above the transfer roll, and means for periodically depressing and raising said pressure member, whereby spaced-apart portions of the under surface of the web are successively subjected to the action of the transfer roll. 100

3. In a match making machine having a carrier for the match splints, splint cutting mechanism, and means for intermittently feeding a web of match stock to present its leading portion to the cutting mechanism and the carrier, a paraffin containing tank located in advance of the feeding means, directly below the path of the web of match stock, a paraffin transfer roll freely rotatable in said tank slightly below the path of the web, a pressure member overhanging said path directly above the transfer roll, and means for depressing and raising said member during the idle periods of the feeding means, whereby spaced-apart portions of the under surface of the web are successively subjected to the action of the transfer roll. 110

4. In a match making machine having a carrier for the match splints, splint cutting mechanism, and means for feeding a web of match stock to the cutting mechanism and the carrier, a paraffin containing tank located in advance of the cutting mechanism, directly below the path of the web of match stock. 125

stock, a paraffin transfer roll mounted to rotate in said tank slightly below the path of the web, a pressure roll overhanging said path directly above the transfer roll, vertically movable bearing boxes in which the pressure roll is journaled, a shaft, means for rotating said shaft, cam means on said shaft, and connections between said cam means and the bearing boxes, whereby the said 10 pressure roll is periodically raised and lowered and the web depressed to subject spaced-apart portions of the under surface of the web to the action of the transfer roll.

5. In paraffin-applying means for a progressing web of match stock, the combination of a tank, a paraffin transfer element in said tank, there being a match stock path normally spaced from said transfer element, and means whereby one surface of the match 20 stock is presented at successive intervals to the action of the transfer element.

6. In paraffin-applying means for a progressing web of match stock, the combination of a tank, a paraffin transfer roll mounted to rotate in said tank, a roll adjacent to and parallel with the transfer roll,

there being a match stock path between said rolls and normally spaced from the periphery of the transfer roll, and means for effecting relative vertical movement between 30 the two rolls in order to present successively spaced portions of one surface of the web of match stock to the transfer roll.

7. In paraffin-applying means for a progressing web of match stock, the combination with means for intermittently advancing the web, of a tank underlying the path of the web, a paraffin transfer roll in said tank, a pressure element overlying the said path directly above the transfer roll, and 35 means for effecting relative vertical movement between said transfer roll and pressure element during the rest periods of the web, whereby spaced-apart portions of the under surface of the web are successively subjected 40 to the action of the transfer roll.

Signed at Springfield, in the county of Hampden and State of Massachusetts this 25th day of May A. D. 1927.

JOSEPH E. ZOMNIR.
CLARENCE L. PFERSCH.
